ALEXANDER GRISWOLD HERRESHOFF, OF NEW YORK, N. Y., ASSIGNOR TO INTERNATIONAL MOTOR COMPANY, OF NEW YORK, N. Y., A CORPORATION OF DELAWARE.

MOUNTING FOR ENGINE ACCESSORIES.

1,317,703.

Specification of Letters Patent. Patented Oct. 7, 1919.

Application filed May 28, 1919. Serial No. 300,314.

To all whom it may concern:

Be it known that I, ALEXANDER GRISWOLD HERRESHOFF, a citizen of the United States, residing in the borough of Manhattan of the city of New York, in the State of New York, have invented certain new and useful Improvements in Mountings for Engine Accessories, of which the following is a specification, reference being had to the accompanying drawing, forming a part hereof.

This invention relates to a novel means for mounting all of the accessories of an internal combustion engine in close proximity to one another and in a position which is most accessible for repairs or adjustments thereof. It has for one of its objects to eliminate much of the shafting which is now commonly employed in the actuation of such accessories and to provide a direct drive for the accessories from the crank shaft of the motor. It has for a further object in a motor adapted for automobile use in which the radiator is mounted at the rear of the hood to mount the accessories at the front end of the engine so that when the hood is raised the accessories will be accessible for demounting or inspection. Still another object of the invention is to provide a unitary support for all such accessories which may, in some embodiments of the invention, constitute a detachable section of the wall of the engine casing. Other advantages of the improved construction will appear as this description proceeds. In the drawing—

Fig. 1 is a view in front elevation of a mounting which comprises a plate adapted to form a detachable section of the engine wall.

Fig. 2 is a view in vertical section taken through the mounting shown in Fig. 1 along the plane indicated by the line 2—2 of Fig. 1 and looking in the direction of the arrows, a portion of the engine casing being indicated.

Fig. 3 is a fragmentary detail view in plan of the improved mounting, one of the units being removed in the interest of clearness.

It will appear hereinafter that the inventive thought underlying the present invention resides in the bringing together of the accessories of an internal combustion engine and so mounting them as to facilitate their assembling, disassembling and inspection while simplifying the operative

driving connections for each such accessory unit. Accordingly, the invention is not to be limited necessarily to the precise embodiment illustrated herein, and it will be apparent that many of the advantages of the improved construction can be realized in other embodiments, as, for instance, where the accessories and their shafts are not supported on a plate which constitutes a section of the engine wall. The drawing shows the application of the accessories to the front end of the engine casing, it being assumed that this engine may be applied for the propulsion of an automobile having the usual radiator mounted at the rear end of the hood. In such a case, it will be evident that when the hood is raised all of the accessories will be exposed at a very accessible place. Further, in the preferred construction, as illustrated, the supporting plate for all of the accessories and their shafts is shown as a detachable section of the front wall of the engine casing.

In the drawing the front engine wall *a* has journaled therein the crank shaft *b* which extends forwardly to permit engagement of suitable ratchet teeth *b'* thereon with a handle, as for initial cranking. This front wall is formed with two openings *a'*, *a''*, adapted to be closed by a plate *c* which may be bolted to the front wall of the casing, as by bolts passing through holes *c'* therein. This plate carries a housing formed of two sections *c²*, *c³* which may be secured together by means of a series of bolts *c⁴* passing through the proximate faces of the sections at suitable points along the line of contact. The crank shaft *b* extends through the casing thus formed on the plate *c* and has keyed within this casing a bevel gear *d* from which the various accessories of the engine are to be driven. Journaled in the upper wall of the casing is a vertical shaft *e*, the bearings *e'* of which may be clamped between the contacting edges of the sections *c²*, *c³* of the casing at this point. This vertical shaft may carry the water pump indicated generally at *f* and extends upward to drive the overhead cam shafts (not illustrated). This shaft *e* has at its lower end a driving bevel pinion *e²* in mesh with the bevel gear *d*. Extending outwardly from one side of the casing formed by the sections *c²*, *c³*, is a shaft *g* which drives the magneto, indicated

- generally at g' . This magneto may be supported on a bracket h clamped or otherwise carried by the sections c^2 , c^3 of the casing. The shaft g of the magneto is preferably inclined downwardly a little. On the inner end of the shaft is keyed a bevel pinion g^2 which meshes with the bevel gear d . At the opposite side of the casing formed by the sections c^2 , c^3 is journaled another shaft i which may drive a generator i' supported on a bracket k clamped or otherwise carried by the sections c^2 , c^3 . This shaft i may be driven by a bevel pinion i^2 disposed within the casing and in mesh with the bevel gear d . Extending downwardly in the casing formed by the sections c^2 , c^3 still another shaft l which may carry at its upper end a bevel pinion l' to mesh with the bevel gear d , and at its lower end an oil pump l^2 disposed below the level of the oil which may extend continuously from within the crank case through the opening a^2 in the wall thereof into the lower portion of the housing formed by the sections c^2 , c^3 . In the section c^3 of the housing may be formed an opening c^5 to receive an oil strainer m and this filler opening may be normally closed by a removable cover plate n , as is usual. The advantages in construction and use of the mounting described for the accessories will be obvious. These accessories are all brought into close proximity with each other so that access may conveniently be had thereto by a workman for inspection or repairs. Intermediate shafting between the crank shaft and the driven unit is eliminated. By removal of the section c^3 of the housing all of the shafts and their driving pinions are exposed to view for removal or adjustment. Further by removing the plate c all of the units may be taken from the engine without disturbing their relative positions in their bearings. The invention, as stated hereinbefore, is not limited to the precise number or form of accessories so mounted, nor to the provision of a supporting plate therefor which constitutes a section of the engine wall. The scope of the invention will appear from the appended claims.
- I claim as my invention:
1. In combination with an internal combustion engine, a crank shaft therefor and accessory units, a gear on the end of the crank shaft without the engine wall, a housing in which said gear is disposed, a plurality of shafts for said units journaled in said housing, and gears on said shafts meshing with said first named gear.
  2. In combination with an internal combustion engine, a crank shaft therefor and

accessory units, a gear on the end of the crank shaft without the engine wall, a housing in which said gear is disposed removably secured to the engine wall, a plurality of shafts for said units journaled in said housing, and gears on said shafts meshing with said first named gear.

3. In combination with an internal combustion engine, a crank shaft therefor and accessory units, a gear on the end of the crank shaft without the engine wall, a housing in which said gear is disposed having a wall to constitute a section of the engine wall, means to secure the housing removably to the engine wall, a plurality of shafts for said units journaled in said housing and gears on said shafts meshing with said first named gear.

4. In combination with an internal combustion engine, a crank shaft therefor and accessory units, a gear on the end of the crank shaft without the engine wall, a housing comprising a plurality of detachable sections in which the gear is disposed, a plurality of bearings secured between the meeting edges of adjacent sections, shafts for said units journaled in said bearings and gears on said shafts meshing with said first named gear.

5. In combination with an internal combustion engine and a crank shaft therefor, a gear on the end of the crank shaft without the engine wall, a housing in which said gear is disposed having a wall constituting a section of the engine wall and communicating with the crank case to form therewith an oil sump, an oil pump mounted in the housing, a shaft for the oil pump within the housing, a gear on the shaft meshing with the gear on the crank shaft, a filler opening formed in the housing and provided with a removable cover plate, and a strainer within the housing communicating with the filler opening.

6. In combination with an internal combustion engine, a crank shaft therefor and accessory units including a water pump, a generator, a magneto and an oil pump, a gear on the end of the crank shaft without the engine wall, a housing comprising a plurality of detachable sections in which the gear is disposed, a plurality of bearings secured between the meeting edges of adjacent sections, shafts directly connected to each of said units and journaled in said bearings, gears on said shafts meshing with said first named gear and supporting brackets carried on the outer wall of the housing for the generator and the magneto.

This specification signed this 24th day of May, A. D. 1919.

ALEXANDER GRISWOLD HERRESHOFF.
